a corporation of DelawareNo Drawing. Application March 1, 1938,
Serial No. 193,348

11 Claims. (Cl. 260—505)

The present invention relates to a new and improved detergent composition and its process of manufacture.

It is known to halogenate kerosene and condense the halide so formed with aromatic hydrocarbons and sulfonate the resulting condensate for use as a detergent. Such processes as heretofore employed used wide fractions of kerosene, and generally wide fractions of kerosene containing undesirable impurities which produced a relatively impure detergent on condensing with the aromatic compound and sulfonating. Again it has heretofore been believed that mono-halogenation of the kerosene fraction only was desired and that the mono-halide so formed only may be advantageously employed in the production of the detergent, and in consequence it was necessary to discard any alkylation products which resulted from any higher halogenation products formed in the halogenation. To maintain this mono-halogenation, the amount of halogenation has heretofore been restricted to a low molecular ratio and preferably below one-third of that required to form the monohalide. This has necessitated handling large volumes of materials and has consequently greatly increased the cost of the final detergent product.

In accordance with the present invention a greatly improved product has been obtained over that heretofore taught by the prior art. Furthermore, it has been discovered according to the present improved process that not only may mono-halogenated kerosene fractions be employed in the condensation step with the aromatic compounds, but that poly-halogenated kerosene fractions may be employed as well. Such a process as now employed has resulted in an improved product and a great saving in the cost of the final detergent product. In the operation of the present invention, it has been found preferable that the kerosene fraction be substantially free from olefines, aromatic compounds, sulfur compounds and be substantially water-white in color. Furthermore, as the unreacted kerosene fractions of higher boiling ranges possess a distilling range near to that of alkylated aromatic compounds, as for example, alkyl benzene, great care must be taken in its removal from the condensation product in order to make certain it has been removed entirely, and that in its removal, contamination or decomposition of the alkyl aromatic compound has not been effected. In operating the process of this invention, this undesirable decomposition and contamination has been obviated.

Furthermore, it has been found that the poly-halogenated paraffins derived from the particular kerosene fraction of the present invention may be condensed with an aromatic compound, as for example an aromatic hydrocarbon, in the presence of a suitable condensation catalyst, as for example aluminum chloride, to produce compounds other than mono-alkylated products, which may be called poly-arylated alkanes, and the resulting poly-arylated alkanes sulfonated with a suitable sulfonating agent to produce a lighter colored product than has heretofore been obtained. While the entire halogenated kerosene fraction is condensed with the aromatic compound, and the resulting product sulfonated according to the preferred process, it may be desirable to distill the alkylated aromatic compounds and separate them from a dark colored high boiling tarry residue in order to obtain the highest detergency and lightest colored product.

It is surprising to learn that when the so-called poly-arylated alkanes, derived from a condensation of a poly-halogenated kerosene fraction and an aromatic compound, are sulfonated and employed alone as detergents, they are relatively low in detergent efficiency, as compared to the sulfonated condensation product of the corresponding mono-halogenated kerosene fraction and the same aromatic compound, yet when the sulfonated poly-arylated alkanes employed admixed with this same sulfonated condensation product of the mono-halogenated kerosene fraction and the corresponding aromatic compound, the combined detergent effect is substantially the same as is that of the product resulting from the mono-halogenated kerosene fraction alone. This is an unforeseen result. Just what the co-action is, it is difficult to state, but apparently different types of detergency take place with an improved total cleaning effect.

In the operation of this invention, it is preferred that a kerosene fraction having a distilling range of 205° C. to 245° C., and substantially free from olefines, aromatics and sulfur compounds be employed, which kerosene fraction is a mixture of saturated aliphatic hydrocarbons boiling in the dodecane and tridecane range.

The following is a specific and preferred embodiment of the invention but is in no sense limitative of the scope thereof.

Five hundred ten (510) parts by weight of a kerosene distillate having a distilling range of substantially 205° C. to 245° C. and being substantially free of olefines, aromatic and sulfur compounds, were chlorinated substantially 50% 55

of the extent stoichiometrically required to form the monochloride at a temperature of 80° C. The mixture of alkyl halide and unhalogenated kerosene was then added at room temperature with 5 agitation to 350 parts by weight of benzene containing 15 parts by weight of anhydrous aluminum chloride. On completion of the addition of the alkyl halide-kerosene mixture, the reactants were heated for an additional period of two hours 10 at 50° C. On the completion of the reaction, the reaction product consists of two layers. The upper layer comprising unchanged benzene, kerosene and alkyl benzene, is separated from the lower or catalyst layer, and the benzene removed 15 by distillation at atmospheric pressure. The unreacted kerosene fraction is removed preferably by distillation at reduced pressure in order to avoid decomposition of the alkyl benzene. The residue comprising the mixed alkyl benzenes of 20 the present invention and mainly mono-alkylated benzene and so-called poly-phenylated alkanes, may be sulfonated without further purification or may be distilled to remove any tarry residual by-products, which I have found adversely affect the 25 detergent properties of the desired product. The alkyl benzenes derived from the mono-halogenated and poly-halogenated kerosene fraction, whether crude or distilled, are carefully sulfonated employing a process so 30 as to obtain a light colored product after conversion to their water-soluble salts. Thus, one convenient method of sulfonation, which produces such a product, comprises the use of 96% sulfuric acid in the ratio of substantially 300 parts by weight of acid to substantially 100 parts by weight of alkyl benzene at substantially 40° C. to 50° C. Another method of sulfonation, which produces a light colored product, comprises the use of 20% oleum in the ratio of substantially 120 parts by weight of acid to substantially 100 parts by weight of alkyl benzene at a temperature of 35 substantially 0° C. to 5° C. It is a preferred embodiment of this invention that the sulfonation step be carefully controlled by temperature regulation and concentration of acid so that a light colored product is obtained after neutralization of 40 the sulfonic acid. The alkyl benzene sulfonic acids may be separated by adding water to the sulfonation mass, whereupon the sulfonic acids 45 separate as an upper layer, which is drawn off and neutralized with caustic soda. The aqueous solution of the sodium salt of the alkylated benzene sulfonic acids may be evaporated to dryness in 50 which case the sodium salt of the alkyl benzene sulfonic acids contains varying amounts of sodium sulfate, or the sodium sulfate may be separated 55 from the sodium salt of the alkyl benzene sulfonic acid by suitable means.

In order to compare the deterutive effectiveness 60 of the detergents obtained, the following wash test was employed.

White cotton fabric was thoroughly desized by washing successively in acid, alkaline and soap baths, the fabric being rinsed after each bath. The fabric so obtained was repeatedly immersed 65 in a soil comprising a suspension of colloidal graphite in a solution of a mineral and vegetable oil in carbon tetrachloride until a baryta whiteness of 27% to 30% was obtained. The fabric was then aged prior to use. The aged strips were 70 cut into six-inch squares and placed in separate pint jars containing 100 c. c. of the solution under test and 10 rubber balls. In all cases the concentration of the wash solution was 0.2% detergent by weight. The jars were closed, clamped 75 in a launderometer and agitated at a tempera-

ture of 140° F. At the end of definite periods of washing, the launderometer was stopped, the fabric removed and given two rinses with 100 c. c. portions of water. The washed fabric was dried and its whiteness determined by means of 5 a Pulfrich photometer, wherein readings give the percent whiteness in comparison with the whiteness of baryta, and a consequent measure of efficiency of the detergent may be determined.

Tests were carried out simultaneously in the 10 manner defined above on the following materials obtained from the sulfonation of the condensation product of halogenated kerosene boiling at 205° C. to 245° C., said kerosene halogenated to the extent of 50% of that required stoichiometrically to form the monohalide and benzene as defined above: (A) the sodium salt of the product obtained from the sulfonation of the mono-alkyl benzenes separated from the total alkylation product by fractionation at reduced 15 pressure, and derived from the mono-halogenated kerosene fraction, (B) the sodium salt of the product obtained from the sulfonation of the poly-phenylated alkanes, comprising the residue remaining after distilling off the above mono- 20 alkylated benzene, and derived from the poly-halogenated kerosene fraction and (C) the sodium salt of the product obtained from the sulfonation of the total crude condensation product of the entire halogenated kerosene fraction and benzene. It was found that while (B) was greatly 25 inferior to (A) in detergent efficiency, (C) was substantially identical with (A) in detergent efficiency.

Detergents were also prepared in a manner 30 analogous to that described above from a halogenated kerosene fraction, said kerosene fraction having a distilling range of 205° C. to 245° C., and wherein the halogenation, for example chlorination, was 60% and 75% respectively of that required to form the monochloride. Detergent 35 tests were also made on the following products obtained therefrom: (A') the sodium salt of the mono-alkylated benzene, (B') the sodium salt of the sulfonated poly-phenylated alkanes and (C') the sodium salt of the sulfonated crude unfractionated total alkyl benzenes. It was found that 40 while (C') the detergent obtained from the crude unfractionated total alkyl benzenes possessed desirable detergent action and was more efficient 45 than was (B'), it was desirable to distill the crude alkyl benzene in order to eliminate a small proportion of tarry dark colored by-products, after which the sodium salt of the total alkyl benzene sulfonic acids was found substantially 50 equal to detergent efficiency to the sodium salt 55 of the mono-alkylated benzene sulfonic acid (A') above.

If desirable, of course, a narrower kerosene fraction may be halogenated, condensed with 60 aromatic compounds, for example benzene, and the total alkylation product, either crude or distilled, sulfonated and employed as efficient detergents according to the present invention. Thus a kerosene fraction distilling between 205° 65 C. and 225° C. has been found to give most desirable results when reacted according to the process of this invention.

Again other aromatic compounds than benzene have been condensed with a halogenated 70 kerosene fraction, said kerosene fraction distilling between 205° C. and 245° C., and the total condensate sulfonated in the manner defined above. Thus I may employ toluene, xylene, diphenyl, chlor diphenyls, naphthalene and the 75

like, and such products are included within the scope of the invention.

Furthermore, other salts of the alkylated aromatic sulfonic acids than the sodium salt may be employed. Water-soluble salts generally may be employed, although the alkali metal salts are preferred.

In the halogenation of the kerosene fraction of the present invention, other proportions of halogen may be employed than hereinbefore set forth in order to produce a mixture comprising mono-halides and a substantial amount of poly-halides for use according to the present invention. It is preferred, however, that halogenation to the extent of more than 33½% and less than 100% of that stoichiometrically required to form the monohalide be effected, in order to obtain the most desirable detergent.

This application is a continuation-in-part of 20 my copending applications Serial No. 88,685, filed July 2, 1936, now patent 2,161,174; and Serial No. 88,625, filed July 2, 1936, now patent 2,161,173.

The present invention is limited solely by the claims attached hereto.

25. What is claimed is:

1. A detergent composition comprising as its essential detergent constituent a mixture of alkali metal salts of monosulfonated monoaryl alkanes and polyaryl alkanes obtained by halogenating a 30 kerosene fraction having a distillation range within the range of approximately 205° C. to 245° C. until a substantial proportion of dihalogenated hydrocarbons admixed with monohalogenated hydrocarbons is produced therein, condensing an aromatic hydrocarbon therewith to obtain an alkylated aromatic hydrocarbon mixture containing monoaryl alkanes and polyaryl alkanes, separating the unhalogenated kerosene fraction from the alkylated aromatic hydro- 40 carbon mixture, sulfonating the alkylated aromatic hydrocarbon mixture and converting the resulting sulfonated product to alkali metal salts.

2. A detergent composition comprising as its essential detergent constituent a mixture of alkali metal salts of monosulfonated monoaryl alkanes and polyaryl alkanes, obtainable by halogenating a kerosene fraction having a distillation range within the range of approximately 205° C. to 245° C. to the extent of less than 100% and more than 50 33½% of that required to form the monohalide, condensing an aromatic hydrocarbon therewith to obtain an alkylated aromatic hydrocarbon mixture containing monoaryl alkanes and polyaryl alkanes, separating the unhalogenated kerosene fraction from the alkylated aromatic hydrocarbon mixture, sulfonating the alkylated aromatic hydrocarbon mixture and converting the resulting sulfonated product to alkali metal salts.

3. A detergent composition comprising as its 60 essential detergent constituent a mixture of alkali metal salts of monosulfonated monoaryl alkanes and polyaryl alkanes obtainable by chlorinating a kerosene fraction having a distillation range within the range of approximately 205° C. to 245° C. until a substantial proportion of dichlorinated hydrocarbons admixed with monochlorinated hydrocarbons is produced therein, condensing an aromatic hydrocarbon therewith to obtain an alkylated aromatic hydrocarbon mixture containing monoaryl alkanes and polyaryl alkanes, separating the unchlorinated kerosene fraction from the alkylated aromatic hydrocarbon mixture, sulfonating the alkylated aromatic hydrocarbon mixture and converting the resulting sulfonated product to alkali metal salts.

4. A detergent composition comprising as its essential detergent constituent a mixture of alkali metal salts of monosulfonated monoaryl alkanes and polyaryl alkanes obtainable by chlorinating a kerosene fraction having a distillation range 5 within the range of approximately 205° C. to 245° C. until a substantial proportion of dichlorinated hydrocarbons admixed with monochlorinated hydrocarbons is produced therein, condensing an aromatic hydrocarbon therewith to 10 obtain an alkylated aromatic hydrocarbon mixture containing monoaryl alkanes and polyaryl alkanes, separating the unchlorinated kerosene fraction from the alkylated aromatic hydrocarbon mixture, purifying the alkylated aromatic hydrocarbon mixture by distillation under reduced pressure, sulfonating said purified alkylated aromatic hydrocarbon mixture, and converting the resulting sulfonated product to alkali metal salts.

20 5. A detergent composition comprising as its essential detergent constituent a mixture of alkali metal salts of monosulfonated monophenyl alkanes and polyphenyl alkanes obtainable by chlorinating a kerosene fraction having a distillation range within the range of approximately 205° C. to 245° C. until a substantial proportion of dichlorinated hydrocarbons admixed with monochlorinated hydrocarbons is produced therein, condensing benzene therewith to obtain an alkylated benzene mixture containing monophenyl alkanes and polyphenyl alkanes, separating the unchlorinated kerosene fraction from the alkylated benzene mixture, sulfonating the alkylated benzene mixture and converting the resulting sulfonated product to alkali metal salts.

25 6. A detergent composition comprising as its essential detergent constituent a mixture of alkali metal salts of monosulfonated monophenyl alkanes and polyphenyl alkanes, obtainable by chlorinating a kerosene fraction having a distillation range within the range of approximately 205° C. to 245° C. to the extent of less than 100% and more than 33½% of that required to form 40 the monochloride, condensing benzene therewith to obtain an alkylated benzene mixture containing monophenyl alkanes and polyphenyl alkanes, separating the unchlorinated kerosene fraction from the alkylated benzene mixture, sulfonating the alkylated benzene mixture and converting the resulting sulfonated product to alkali metal salts.

45 7. A detergent composition comprising as its essential detergent constituent a mixture of alkali metal salts of monosulfonated monophenyl alkanes and polyphenyl alkanes obtainable by chlorinating a kerosene fraction having a distillation range within the range of approximately 205° C. to 245° C. until a substantial proportion of dichlorinated hydrocarbons admixed with 55 monochlorinated hydrocarbons is produced therein, condensing benzene therewith to obtain an alkylated benzene mixture containing monophenyl alkanes and polyphenyl alkanes, separating the unchlorinated kerosene fraction from the alkylated benzene mixture, purifying the alkylated benzene mixture by distillation under reduced pressure, sulfonating said purified alkylated benzene mixture, and converting the resulting sulfonated product to alkali metal salts.

60 8. A detergent composition comprising as its essential detergent constituent a mixture of sodium salts of monosulfonated monophenyl alkanes and polyphenyl alkanes obtainable by chlorinating a kerosene fraction having a dis- 75

illation range within the range of approximately 205° C. to 245° C. until a substantial proportion of dichlorinated hydrocarbons admixed with monochlorinated hydrocarbons is produced 5 therein, condensing benzene therewith to obtain an alkylated benzene mixture containing mono-phenyl alkanes and polyphenyl alkanes, separating the unchlorinated kerosene fraction from the alkylated benzene mixture, sulfonating the 10 alkylated benzene mixture and converting the resulting sulfonated product to sodium salts.

9. A detergent composition comprising as its essential detergent constituent a mixture of sodium salts of monosulfonated monophenyl al-15 kanes and polyphenyl alkanes, obtainable by chlorinating a kerosene fraction having a distillation range within the range of approximately 205° C. to 245° C. to the extent of less than 100% and more than 33½% of that required to form 20 the monochloride, condensing benzene therewith to obtain an alkylated benzene mixture containing monophenyl alkanes and polyphenyl alkanes, separating the unchlorinated kerosene fraction from the alkylated benzene mixture, sulfonating 25 the alkylated benzene mixture and converting the resulting sulfonated product to sodium salts.

10. A detergent composition comprising as its essential detergent constituent a mixture of sodium salts of monosulfonated monophenyl al-30 kanes and polyphenyl alkanes obtainable by chlorinating a kerosene fraction having a distillation range within the range of approximate-

ly 205° C. to 245° C. until a substantial proportion of dichlorinated hydrocarbons admixed with monochlorinated hydrocarbons is produced there-5 in, condensing benzene therewith to obtain an alkylated benzene mixture containing mono-phenyl alkanes and polyphenyl alkanes, separating the unchlorinated kerosene fraction from the alkylated benzene mixture, purifying the alkylated benzene mixture by distillation under reduced pressure, sulfonating said purified alkylated benzene mixture, and converting the resulting sulfonated product to sodium salts. 10

11. In the process of producing an alkali metal salt of an alkylated aromatic monosulfonic acid having detergent properties, comprising the 15 steps of halogenating a kerosene fraction distilling between 205° and 245° C., condensing an aromatic hydrocarbon therewith to form an alkylated aromatic hydrocarbon mixture, separating the unreacted kerosene fraction from said 20 alkylated aromatic hydrocarbon mixture, sul-25 fonating the alkylated aromatic hydrocarbon mixture and transforming the resulting alkylated aromatic sulfonic acid to an alkali metal salt, the improvement consisting in halogenating the kerosene fraction until a substantial proportion 30 of dihalogenated hydrocarbons admixed with monohalogenated hydrocarbons is formed there- in and thereafter condensing this halogenated fraction with the aromatic hydrocarbon. 30
